UNITED STATES PATENT OFFICE.

REX H. TAYLOR, OF ROCHESTER, NEW YORK.

INFLATED BALL.

1,279,936.

Specification of Letters Patent. Patented Sept. 24, 1918.

Application filed November 8, 1917. Serial No. 200,907.

To all whom it may concern:

Be it known that I, REX H. TAYLOR, a citizen of the United States, residing at Rochester, county of Monroe, State of New York, have invented a certain new and useful Improvement in Inflated Balls, of which the following is a specification, reference being had therein to the accompanying drawings.

10 My invention has for its object a new and improved ball capable of being inflated and for use according to its shape and size as a foot ball, basket ball or for gymnasium purposes. Balls of this type have a cover of 15 leather or fabric within which is a rubber bladder which is impervious to air and which is inflated to give the ball whatever degree of hardness is required. My invention has for its object to do away with the 20 protruding stem through which the bladder is inflated and which has heretofore usually been bent over and tucked in between the cover and the bladder producing a bunch at that point and rendering the ball unsymmetrical in shape. My invention also furnishes means for preventing the bladder from creeping or otherwise becoming displaced relatively to the cover. The ball is 25 easier to inflate and can be tested for pressure at any time by the use of a suitable pressure gage.

The ball embodying my invention is no more expensive to construct than balls of the type heretofore in use and presents a surface 30 which is free from bunches and which is symmetrical and true.

The invention will be fully understood from the following description taken in connection with the accompanying drawings 35 and the novel features thereof will be pointed out and clearly defined in the claims at the close of this specification.

In the drawings, Figure 1 is a plan view of a ball embodying my invention.

40 Fig. 2 is a longitudinal section of the ball shown in Fig. 1.

Fig. 3 is a view of the ball with the bladder in place and the flap turned out.

Fig. 4 is a section of the air valve.

45 Referring now to the drawings, at A is shown the cover preferably of leather or similar material, the nature of which depends upon the use to which the ball is to be put. At 11 is shown the usual opening 50 closed by a lacing 12. Within the cover is a bladder 13 composed of thin elastic sheet

rubber impervious to air. The bladder and cover are of well known form and construction and therefore do not need to be described in further detail. At 14 is shown an air valve tube which projects into the interior of the bladder and has a head 15 which extends laterally and is substantially flush with the surface of the bladder. Within this air valve tube 14 is a movable valve member 16 and spring 17 by which the air valve is held closed normally. The air valve seats against a valve seat 18 and is also held forcibly against it by the pressure of the air contained within the ball when it is inflated. The air valve stem 19 protrudes to a point about on a level with the end of the tube so that it may be pushed inward to discharge the air contained within the bladder when it is desired to deflate the bladder. The foregoing parts are of the form of the ordinary tire valve used on bicycle and automobile tires. In practice, I find it convenient to use the tire valve known on the market as the Schrader valve. The end of the valve tube 20 is closed by a cap 19 having a central tubular projection 20 which is screw threaded for engagement with the interior of the bore of the outer end of the valve tube. This cap has a slotted head for engagement with a tool and has a protruding flange 21, which is about the size of the head of the valve tube 14.

At 22 is shown a flap sewn to the interior of the cover and preferably made of leather or strong material. This flap is shown in Fig. 3 as pulled out from the interior of the cover to expose to view the bladder and air valve from which the cap has been removed. In this flap, is a hole 23 located so that when the flap is in place it will be directly over the head of the air valve. After the bladder has been put in place the flap is tucked in and the pump attached through the hole 23 in the flap. The ball is then inflated. The position of the flap is shown in dotted line at 22 in Fig. 1. After the ball is inflated the pump connection is unscrewed and the cap 19 is screwed in place with its cylindrical projection 20 extending through the hole 23 and into the tubular bore in the valve tube. When the valve cap has been screwed down tightly it compresses the flap around the margin of the hole 23 firmly between the end of the valve tube and the head of the cap and secures the bladder firmly to the flap and thereby to the cover. The ball is

then laced by the lacing 12 in the ordinary manner.

It will be seen that since the valve tube extends inwardly and has its head substantially flush with the outer surface of the bladder that the ball when inflated will be perfectly true and there will be no perceptible bunch to cause any distortion of the ball. The tube is so located that although being made of metal, it cannot do any injury to any person using the ball. Since the valve tube is not exposed, it cannot be bent with relation to the bladder, and therefore there is no tendency to break the tube or the adjacent portions of the bladder. The ball is therefore much more durable than those as heretofore constructed. The cap 19, valve tube 14 and flap 22 together form means for securing the bladder in place in the ball so that it cannot turn around or creep and become displaced.

What I claim is:

1. The improved inflated ball comprising a cover having an opening, a flap secured to the inside of the cover adjacent the opening and having a hole therein, a bladder having an air tube and valve for said bladder, and a cap having a stem passing through said hole in the flap and engaging the valve tube and securing the said bladder to the flap and thereby to the cover, the cover overlying the said cap.

2. The improved inflatable ball comprising an inner casing of flexible material, a valved air tube attached thereto, a cover casing of flexible material having an opening for insertion of the inner casing when the inner casing is in collapsed condition, said cover having a flap secured to the inside thereof adjacent one side of said opening and spreading over the end of said air tube and under the cover on the opposite side of said opening, said flap being formed with a hole in alignment with the hole in the air tube, a detachable cap for the air tube having a flange which engages the flap and clamps it to the inner casing, and means for lacing up the said opening so that the said cover extends over the outside of the cap.

3. The improved inflatable ball comprising an air tight inner flexible casing, a valved air tube extending into the interior of the said casing and having a flanged outer end secured to said casing substantially

flush therewith, a cover casing of flexible material having a slit therein to permit the insertion of the inner casing when the latter is in a collapsed condition, a flap secured to the inner face of the cover casing adjacent one side of said slit and having a free edge portion which is tucked under the cover on the opposite side of the slit, said flap being formed with a hole in alignment with the hole in the air tube and a removable cap for the air tube having a screw threaded stem which passes through said hole in the flap and is screwed into engagement with the air tube, said cap having a flange which engages the outer face of the flap and clamps it to the inner casing, and means for lacing up the said slit in the cover outside of said cap.

4. The improved inflatable ball comprising a bladder, a valved air tube attached thereto and extending into the interior thereof, a cover having a slit for inserting the collapsed bladder into the cover, a flap secured to the inside of said cover adjacent one side of said slit, the other edge of the flap being free and tucked under the cover on the opposite side of said slit, said slit being formed with a hole in alignment with the hole in the air tube and a removable cap for the air tube having a stem which passes through said hole in said flap and is formed for engagement with the air tube and having a flange which engages with the outer face of the flap and clamps it to the bladder, the said cap being overlaid by the cover, and a lacing for said slit.

5. The improved inflatable ball comprising an inner casing of flexible material, a valved air tube attached thereto and having a cap, a cover casing of flexible material having an opening for inserting the inner casing, said cover having a flap secured to the inside thereof and extending across the said opening on the inside of the cover and being formed with a hole in alignment with the hole in the air tube, means for securing the flap to the inner casing, and means for fastening together the edges of the cover at the sides of the opening in such manner that the cover is substantially closed outside of the cap of the air tube.

In testimony whereof I affix my signature

REX H. TAYLOR.
